UNITED STATES PATENT OFFICE

SURGICAL APPARATUS FOR MEASURING AND REGULATING VACUUM PRESSURES

John Ognanovich, Fort Snelling, Minn.

Application December 12, 1951, Serial No. 261,266

This invention relates to surgical apparatus and particularly to devices for withdrawing blood from the body and also for withdrawing body fluids from areas in which surgery is performed, such as after chest and abdominal operations, and in particular a container having one connection to a vacuum pump, another connection adapted to extend to a patient, another connection to a gage and water reservoir and a fourth connection to a bleeder or air inlet or needle valve.

The purpose of this invention is to provide suction apparatus for withdrawing blood and other fluids from the human body in which means is provided for accurately regulating and maintaining a negative or vacuum pressure continuously as the apparatus is used.

The general range of pressure used in surgical cases is from 12 to 17 centimeters of water and with the conventional type of apparatus it is difficult to control the fluctuating pressures resulting from the extraction of blood or other body fluids at these comparatively low pressures. With this thought in mind this invention contemplates a vacuum pressure control unit wherein a wide mouth glass jar is directly connected to a suction or vacuum pump and with the jar and pump positioned in an open housing and the jar connected to a gage or water manometer and to a needle valve and also having a suction connection with a needle thereon the amount of the suction is readily adjustable by the needle valve.

The object of this invention is, therefore, to provide a surgical apparatus in which comparatively low vacuum or suction pressures are held constant.

Another object of the invention is to provide a suction control device particularly adapted for use in surgery in which the device may be used in combination with apparatus in existence in an operating room or laboratory.

A further object of the invention is to provide a fluid suction device particularly adapted for use in surgery, in which the device is of a comparatively simple and economical construction.

With these and other objects and advantages in view the invention embodies a substantially open housing having a shelf therein with a container positioned upon the shelf, a suction pump positioned below the shelf, a manometer positioned on one end of the housing, a needle valve positioned on the end of the housing on which the manometer is positioned and suitable connections connecting the container to the pump.

PATENT OFFICE

TUS FOR MEASURING VACUUM PRESSURES

Fort Snelling, Minn.

12-1951 Serial No. 261-366

12, 1951, Serial No. 261,266

(Cl. 128-278) **2** medical and of other art
and is substantially as in the drawing and
manometer, and needle valve and also for con-
necting the container to a needle or other device
for extracting blood and other fluids from the
body.

5 Other features and advantages of the invention will appear from the following description taken in connection with the drawings wherein:

Figure 1 is a front elevational view illustrating the apparatus and showing a container on a shelf between end walls of a housing and a vacuum pump also between the end walls and mounted on a base from which said end walls extend.

15 Figure 2 is an end elevational view looking toward the end upon which the manometer and needle valve are positioned.

Figure 3 is a diagrammatic view illustrating a wide mouth container and showing tubes extended therefrom providing connections to a suction pump, manometer, and needle valve and also having a connection adapted to be extended to a patient.

25 Referring now to the drawings wherein like reference characters denote corresponding parts the improved suction apparatus of this invention includes a wide mouth container 10, a vacuum pump 11, a water manometer 12, a needle valve 13, and a housing having a base 14, end walls 15 and 16, a back 17 and a support 18.

30 The container 10, which is preferably formed of glass, a transparent plastic or other suitable material is provided with a stopper 19 of resilient material and the stopper is provided with a plurality of passages 20 to which tubes to the 35 pump, gage and valve extend and through which a tube 21 for a needle or other suction device that may be used in the patient extends.

The vacuum or suction pump 11 is connected to the container by a tube 22, the manometer 12 by a tube 23 and the needle valve 13 by a tube 24.

The lower end of the manometer 12, to which the tube 23 is connected, is provided with a water reservoir 25 and a scale providing a gage 26 extends from the reservoir upwardly in close proximity to the gage or tube whereby pressures are readily observed and as the level of the water moves upwardly air is admitted into the container 10 through the needle valve 13 to break the vacuum and thereby relieve the pressure.

50 By this means the needle valve 13 provides a control device through which air is bled into the system as the pressure increases. With the needle valve 13 closed pressure will build up in the container 10 and tubes of the system and 55 when greater pressures which are not desired are

indicated on the gage the needle valve 13 is opened so that air is bled into the system to relieve the pressure.

The valve 13 is provided with a filter as indicated by the numeral 27 which is connected to a vertical section of the tube 24 to prevent dust and dirt clogging the orifice of the valve.

With one hand of the operator on the valve 13 constant pressure may be maintained in the system.

The lower ends of the end walls are secured to a section 28 on the base by screws 29 and the upper ends of the walls are secured to the support 18 by screws 30.

The housing is also provided with a shelf 31 upon which the container 10 is positioned and the shelf is held between the end walls with screws 32.

It will be understood that modifications may be made in the design and arrangement of the apparatus without departing from the spirit of the invention.

What is claimed is:

In a surgical apparatus for measuring and

regulating vacuum pressures, a housing including a horizontally disposed base for supporting a pump, a pair of spaced parallel side walls extending upwardly from said base and secured thereto, one of said side walls adapted to have a vertically disposed manometer connected thereto, a horizontally disposed shelf arranged above said base for supporting a container, and a vertically disposed back wall projecting upwardly from said base and connected to said side walls, a tube extending from the container and including a vertically disposed portion, a needle valve connected to the vertically disposed portion of said tube, and a filter connected to the lower end of said vertically disposed portion.
